US0D1069860S

(12) **United States Design Patent** (10) Patent No.: **US D1,069,860 S**
(45) Date of Patent: ** Apr. 8, 2025

(54) **ICE CUBE TRAY**

(71) Applicant: **ICEBREAKER International ApS**,
Aalborg (DK)

(72) Inventor: **Kim Jensen**, Aalborg (DK)

(73) Assignee: **ICEBREAKER International ApS**,
Aalborg (DK)

(**) Term: **15 Years**

(21) Appl. No.: **35/521,019**

(22) Filed: **Apr. 19, 2024**

(80) **Hague Agreement Data**

Int. Filing Date: **Apr. 19, 2024**

Int. Reg. No.: **DM/237211**

Int. Reg. Date: **Apr. 19, 2024**

Int. Reg. Pub. Date: **May 31, 2024**

(30) **Foreign Application Priority Data**

Oct. 19, 2023 (WO) WIPO139847

(51) LOC (15) Cl. **15-07**

(52) U.S. Cl.

USPC **D15/90**

(58) **Field of Classification Search**

Property Law; Margaret Polson

(57) **CLAIM**

The ornamental design for an ice cube tray as shown and
described.

DESCRIPTION

1. Ice cube tray
2. Ice cube tray
- 1.1 : Perspective
- 1.2 : Perspective
- 1.3 : Front
- 1.4 : Left
- 1.5 : Right
- 1.6 : Top
- 1.7 : Bottom
- 1.8 : Back
- 2.1 : Perspective
- 2.2 : Perspective
- 2.3 : Front
- 2.4 : Left
- 2.5 : Right
- 2.6 : Top
- 2.7 : Bottom
- 2.8 : Back

The reproductions show the design of two new ice cube
trays; the reproductions are rendered images in grey tones,
as protection is not claimed for any specific-colors; design 1

(Continued)

shows different parts in different colors to represent different materials; design 2 has parts in a transparent material.

1 Claim, 16 Drawing Sheets
